United States Patent Office

Des. 225,544

Patented Dec. 19, 1972

225,544

VEHICULAR TOY

Norman Spiegel, 145 E. 15th St.,
New York, N.Y. 10003

Filed Apr. 27, 1971, Ser. No. 138,013

Term of patent 14 years

Int. Cl. D21—01

U.S. Cl. D34—15

FIG. 1

FIG. 2

FIG. 3

FIG. 1 is a perspective view generally from in front of and above of a vehicular toy embodying my new design;

FIG. 2 is a side elevational view thereof; and

FIG. 3 is a rear elevational view thereof.

I claim:

The ornamental design for a vehicular toy, as shown.
